UNITED STATES PATENT OFFICE

139,225

DESIGN FOR A BASE SECTION OF A HOT-WATER SUPPLY BOILER

Morris H. Garfunkle, Newark, N. J.

Application November 27, 1943, Serial No. 111,801

Term of patent 14 years

(Cl. D81—2)

To all whom it may concern:

Be it known that I, Morris H. Garfunkle, a citizen of the United States, residing at Newark, in the county of Essex and State of New Jersey, have invented a new, original, and ornamental Design for a Base Section of a Hot-Water Supply Boiler, of which the following is a specification, reference being had to the accompanying drawing, forming part thereof.

In the drawing:

Figure 1 is a top plan view of a base section

of a hot-water supply boiler showing my new design,

Figure 2 is a rear elevational view of the same,

Figure 3 is a front elevational view of the same, and

Figure 4 is a side elevational view of the same.

I claim:

The ornamental design for a base section of a hot-water supply boiler, substantially as shown.

MORRIS H. GARFUNKLE.
